J. OLMS TED.

ELECTRO MAGNETIC CAR BRAKE.

No. 89,495.

Patented Apr. 27, 1869.

JOSEPH OLMSTED, OF GALESBURG, ILLINOIS.

Letters Patent No. 89,495, dated April 27, 1869.

IMPROVEMENT IN ELECTRO-MAGNETIC CAR-BRAKES.

The Schedule referred to in these Letters Patent and making part of the same.

To all whom it may concern:

Be it known that I, JOSEPH OLMSTED, of Galesburg, in the county of Knox, and State of Illinois, have invented certain new and useful Improvements in Electro-Magnetic Car-Brakes; and I do hereby declare that the following is a full, clear, and exact description of the construction and operation of the same, reference being had to the accompanying drawings, making a part of this specification, in which—

Figure 1 is a perspective view.

Figure 2 is a top plan or view of part of the device.

Figure 3 is a side view of the brake-bars and the ever for operating the same.

Figure 4 is a perspective view, showing the connection of the circuit with the revolving magnets, seen from point 19, fig. 1.

Figure 5 is a side view of the device for connecting the wires between the cars.

Figure 6 is a cross-section of fig. 4, on the plane of the line 9-9.

Figure 7 is a cross-section of fig. 2, on the line 8-8.

This invention relates to improvements in electro-magnetic car-brakes; and

The invention consists—

First, in connecting the circuit with magnets and armature, by means of a revolving connection, with two or more bearings upon each connection ring, each being independent of the other, and joined to one common conductor, thereby securing a sure connection.

Second, in the arrangement of an armature, the shaft of which gears with the car-axle, and communicates the motion of said axle to the shaft carrying the magnets, on the completion at any time of the electric circuit.

Third, in an adjustable armature-plate, as hereafter fully described.

Similar letters of reference indicate corresponding parts in all of the drawings.

Letter A represents an ordinary single truck-frame.

B represents the wheels, and

f, the axles of the frame A.

U represents a shaft, supported in bearings T T in the braces S' S'.

Z represents a circular disk or friction-plate, permanently attached to the shaft U.

y y, fig. 2, represent horse-shoe magnets, the poles of which are permanently attached to and seated in the plate Z, and insulated by brass or other insulating fastenings.

k' k, figs. 4 and 6, represent rings, grooved on their outer surfaces, and attached to the shaft U, by the insulators l l. The electric wire passes from one of these rings k', and forming the helices y y, returns, and passing through the insulator l, connects with the other ring k.

W' W represent wires, supported by the brace i, and having at their lower ends, arms n' of spring wire, fitting in the grooved rings k' k, and bent or curved, as shown at fig. 6, in such a way as to always strike the ring k, in two or more places, so as to always preserve a sure connection between the wires W and the rings k' k.

The springs h h serve to keep the wires W' W always pressed close to the rings k' k.

X X represent the electric wires, proceeding from the poles of the battery, which may be placed in any suitable place on the train. One of the wires is cut in two where it passes the top of wires W' W, and one of the cut ends of it attached to wire W', and the other to wire W.

2, fig. 2, is represented in a line with shaft U. This shaft 2 is supported by brackets S S, and carries on one end the armature a, and near its centre the cog-wheel d.

e represents a pinion-wheel on the car-axle f, and gearing with the wheel d, in such way that the shaft 2, wheel d, and armature a are always revolving with the car-axle.

C represents the ordinary car-brake bars.

G G represent levers pivoted to the brake-bars by the clevis H.

z is a rod, connecting the lower ends of the levers G G.

K is a chain and rod, connecting the upper end of the levers G G.

M represents a lever, pivoted between the pieces R, and carrying two pulleys, N and P, the chain K being passed over the upper pulley and under the lower one.

J represents a chain, connecting the lower end of lever M with the shaft U, so that revolving the said shaft U will, by winding up the chain j, draw with greatly increased power, through the medium of the said levers, on the brakes.

r represents a block, secured in each end of every car, with flat wires s, attached thereto, as shown at fig. 5, in such manner that their outer ends will always spring together, or close automatically.

t, fig. 5, represents a dart-shaped block, one of which is attached to either end of a cord, of any suitable length, and carrying the two wires X X. The darts T being slipped between the spring-jaws s, in the adjacent ends of two cars, will form the proper circuit connections, and at any time should part of the train be detached, and the dart be withdrawn, the spring-jaws s will close, and the circuit may still be completed.

Fig. 7 shows a cross-section of armature-plate a, fig. 2, on the line 8 8, and the manner of inserting the shaft 2, with a spline, 3, cast solid thereon, so that the plate a may be held firmly in the direction of its revolutions with the shaft 2, and be allowed freedom in

other directions for the purpose of allowing it to always adjust itself exactly to the face of the friction-plate Z.

The manner of applying my invention will be obvious from the foregoing description.

The batteries being arranged with keys for opening and closing the circuit, the moment the circuit is closed, the armature *a* will be attracted by, and adhere to, the poles of the magnets *y y*, at the same time magnetizing and adhering to the friction-plate Z, thereby imparting the revolving motion of the armature to the plate Z and shaft U, winding the chain *j* on shaft U, and applying the brakes, and the moment the circuit is broken, and the magnetic attraction lost, the brakes will be released.

The brake-bars C being attached to the cars in the usual method, the whole device admits of being applied to the ordinary brakes and attachments.

Having thus described my invention,

What I claim as new, and desire to secure by Letters Patent, is—

1. The insulated grooved rings *k' k*, the wires W"

W, having arms with two or more bearings on the rings *k*, springs *h h*, and shaft U, arranged substantially as described, and for the purpose set forth.

2. The arrangement of the pinions *e* and *d*, shaft 2, and revolving armature *a*, for transmitting motion to the friction-plate Z and shaft U, substantially as described.

3. The arrangement of the shaft U, friction-plate Z, and the insulated magnets *y y*, all constructed and operating in the manner and for the purposes herein set forth and described.

4. The revolving armature-plate *a*, loosely attached as described, to the shaft 2, so that the plate *a* may be held firmly in the direction of its revolutions with the shaft 2, and be allowed freedom in other directions, for the purpose of allowing it to always adjust itself exactly to the face of the friction-plate Z.

Signed at Galesburg, this 21st day of October, 1868.

JOSEPH OLMSTED.
